US0D1010603S

(12) **United States Design Patent** (10) Patent No.: **US D1,010,603 S**
(45) Date of Patent: ** Jan. 9, 2024

(54) **INTERFERENCE DEVICE**

- (71) Applicant: **SHENZHEN AWP TECHNOLOGY CO., LTD.**, Shenzhen (CN)
- (72) Inventors: **Tijun Bie**, Guangdong (CN); **Long Chen**, Guangdong (CN); **Weidong Ma**, Guangdong (CN)
- (73) Assignee: **SHENZHEN AWP TECHNOLOGY CO., LTD.**, Shenzhen (CN)
- (**) Term: **15 Years**
- (21) Appl. No.: **35/514,772**
- (22) Filed: **Jun. 29, 2022**

(80) **Hague Agreement Data**

- Int. Filing Date: **Jun. 29, 2022**
Int. Reg. No.: **DM/222098**
Int. Reg. Date: **Jun. 29, 2022**
Int. Reg. Pub. Date: **Jul. 22, 2022**

(57) **CLAIM**

The ornamental design for an interference device, as shown and described.

DESCRIPTION

Fig. 1.1 is a front view of an interference device showing our new design;

Fig. 1.2 is a rear view thereof;

Fig. 1.3 is a left side view thereof;

Fig. 1.4 is a right side view thereof;

Fig. 1.5 is a top view thereof;

Fig. 1.6 is a bottom view thereof; and

Fig. 1.7 is a top perspective view thereof.

The broken lines in the figures depict portions of the interference device that form no part of the claimed design.

1 Claim, 7 Drawing Sheets
